UNITED STATES PATENT OFFICE.

GEORGE W. WARDWELL, OF SOUTH NORWALK, CONNECTICUT, ASSIGNOR TO THE HILL
COMPRESSOR & PUMP COMPANY, OF NEW YORK, N. Y., A CORPORATION OF DELA-
WARE

ROTARY PUMP.

Application filed October 25, 1923. Serial No. 670,686.

To all whom it may concern:

Be it known that I, GEORGE W. WARDWELL, a citizen of the United States, residing at South Norwalk, in the county of 5 Fairfield and State of Connecticut, have invented a new and useful Improvement in Rotary Pumps, of which the following is a specification.

This invention relates to rotary pumps of 10 the type having an internally toothed driving gear engaging with an externally toothed driven gear of a different number of teeth, for pumping and compressing fluids, more particularly gases.

15 The object of the invention is to provide a very simple means whereby the pressure accumulated by the pump may be utilized for keeping the working joints sealed and lubricated.

20 This object is attained by fitting the rotor, which contains and actuates the co-operating gears, so that it will float axially in the pumping chamber, and providing spring means that initially push the rotor and 25 gears against the end of the pumping chamber, said means being located in a cavity that is connected to receive discharge pressure, and so arranged as to retain discharge pressure back of the rotor in such manner 30 that the pressure will effect the operating seal supplemental to the initial seal caused by the spring means.

In the accompanying drawings Fig. 1 shows a central longitudinal section of a 35 pump that embodies the invention. Fig. 2 shows a face view of the pump with the head removed. Fig. 3 shows a transverse section on the plane indicated by the dotted line 3—3 on Fig. 1. Fig. 4 shows a modified 40 form of spring sealing means. Fig. 5 shows another modification.

The casing 1 which is generally circular in sectional outline, contains a cylindrical pumping chamber 2 that is closed on one 45 end by a head 3 which is fastened to the casing by any suitable means. The casing has an intake passage 4 on one side and a discharge passage 5 on the other side while the head has an intake port 6 leading from 50 the intake passage to the pumping chamber and a discharge port 7 leading from the pumping chamber to the discharge passage.

55 Rotatably fitting and having a slight movement axially in the pumping chamber is a rotor 8. The hub 9 of the rotor is

mounted on anti-friction bearings 10. The driving shaft 11 is splined in the hub of the rotor so that while the shaft will turn the rotor it will not interfere with the axial movement of the rotor.

Fastened to the rotor is an internally toothed gear 12 and engaging the teeth of this gear are the teeth of an externally toothed gear 13. The externally toothed gear is mounted on anti-friction bearings 14 that are supported by a stud 15 fastened in the head. The stud is positioned out of line with the driving shaft so that the axis of the externally toothed gear will be eccentric to the axis of the internally toothed gear. One of these gears has more teeth than the other and they coact in a well known manner to effect the pumping or compression of fluids.

In a cavity 16 that communicates with the pumping chamber and fastened gas-tight against the end of the hub of the rotor is a diaphragm 17 which is somewhat elastic, and thrusting between this diaphragm and the inner race ring 18 of the anti-friction bearing is a conical spring 19. Secured to the back of the diaphragm is a hardened ring 20 which is semi-circular in cross section and which fits a semi-circular groove in a hardened ring 21 that is tightly set in the end of the cavity that contains the anti-friction bearing, spring and diaphragm. This cavity communicates with the pumping chamber back of the rotor and is connected by a pipe 22 with the discharge from the 90 pump or the reservoir to which the discharge leads, so that discharge pressure accumulated by the pump will be exerted in the cavity. Lubricant is placed in this cavity.

The tension of the diaphragm forces the rotor forward and presses the rotor and contained gears against the inner face of the head so that under low pressure, as on the start of the pump, the pumped fluid will not leak across the faces of the gears. As the pump accumulates pressure its force is exerted in the chamber in such manner that it presses the diaphragm back causing the rings to seat tightly and at the same time is exerted on the back of the rotor so as to force the rotor and the gears against the face of the head and effect a sealing proportional to the degree of pressure. As the rings are forced together by the accumulated

discharge pressure this end of the pressure cavity is tightly sealed. A simple stuffing box 23 is arranged to keep any lubricant from leaking out along the shaft.

5 In the form shown in Fig. 4 the diaphragm 24 attached to the end of the rotor hub, is corrugated in order that it may have sufficient spring to effect the initial sealing. When made in this way it is unnecessary to employ the spiral spring, for the tension of the corrugated diaphragm keeps the joint between the rings tight and the joint between the gears and the face of the head tight and permits the discharge 10 pressure to accumulate sufficiently to effect the tight sealing which is required to render the pump efficient. Such lubricant as is forced by the pressure between the wearing surfaces will pass out of the pump 15 and drain back to the pressure chamber.

In the form shown in Fig. 5 the diaphragm is, instead of being fastened directly to the hub of the rotor as in the two forms described, fastened to a sleeve 26 25 which is keyed to the shaft but has a longitudinal movement in a recess 27 in the hub of the rotor. With this construction the spring normally tends to separate the diaphragm and the rotor so as to keep the parts sealed under the initial tension.

The invention claimed is:—

1. A rotary pump comprising a casing containing a pumping chamber and a pressure cavity communicating with the pumping chamber, a rotor rotatable in and having an axial movement in said chamber, means actuated by said rotor for pumping fluid, a yielding diaphragm in the pressure cavity, said diaphragm having a fluid-tight 35 connection with the rotor and closing one end of the cavity, and means for conducting pressure accumulated by the pump to the pressure cavity, between the diaphragm and the back of the rotor.

45 2. A rotary pump comprising a casing containing a pumping chamber and a pressure cavity communicating with the pumping chamber, a rotor rotatable in and having an axial movement in said chamber, internally toothed and externally toothed intermeshing gears actuated by said rotor for pumping fluid, a yielding diaphragm in the pressure cavity, said diaphragm having a fluid-tight 50 connection with the rotor and closing one end of the cavity, and means for conducting pressure accumulated by the pump to the pressure cavity, between the diaphragm and the back of the rotor.

3. A rotary pump comprising a casing 60 containing a pumping chamber and a pressure cavity communicating with the pumping chamber, a rotor rotatable in and having an axial movement in said chamber, means actuated by said rotor for pumping fluid, a diaphragm in the pressure cavity

connected with the rotor and closing one end of the cavity, a spring in the pressure cavity and thrusting between the diaphragm and the rotor, and means for conducting pressure accumulated by the pump to the pressure cavity, between the diaphragm and the back of the rotor. 70

4. A rotary pump comprising a casing containing a pumping chamber and a pressure cavity communicating with the pumping chamber, a rotor rotatable in and having an axial movement in said chamber, means actuated by said rotor for pumping fluid, a diaphragm in the pressure cavity fixed fluid-tight to the rotor, a ring fixed 75 to the back of said diaphragm engaging a ring in the end of the pressure cavity, and means for conducting pressure accumulated by the pump to the pressure cavity, between the diaphragm and the back of the rotor. 80

5. A rotary pump comprising a casing containing a pumping chamber and a pressure cavity communicating with the pumping chamber, a rotor rotatable in and having an axial movement in said chamber, means actuated by said rotor for pumping fluid, a diaphragm in the pressure cavity fixed fluid-tight to the rotor, a ring fixed 90 to the back of said diaphragm engaging a ring in the end of the pressure cavity, a spring in the pressure cavity and thrusting between the diaphragm and the rotor, and means for conducting pressure accumulated by the pump to the pressure cavity, between the diaphragm and the back of the 95 rotor.

6. A rotary pump comprising a casing containing a pumping chamber and a pressure cavity communicating with the pumping chamber, a rotor rotatable in and having an axial movement in said chamber, means actuated by said rotor for pumping fluid, a corrugated diaphragm in the pressure cavity fixed fluid-tight to the rotor and closing one 105 end of the cavity, and means for conducting pressure accumulated by the pump to the pressure cavity, between the diaphragm and the back of the 110 rotor.

7. A rotary pump comprising a casing containing a pumping chamber and a pressure cavity communicating with the pumping chamber, a rotor rotatable in and having an axial movement in said chamber, bearings supporting said rotor, internally toothed and externally toothed intermeshing 115 gears actuated by said rotor for pumping fluid, a diaphragm in the pressure cavity fixed fluid-tight to the rotor and closing one end of the cavity, a spring in the pressure chamber and thrusting between the diaphragm and the rotor bearings, and means for conducting pressure accumulated by the pump to the pressure cavity, between the diaphragm and the back of the rotor. 120

8. A rotary pump comprising a casing 125

containing a pumping chamber and a pressure cavity communicating with the pumping chamber, a rotor rotatable in and having an axial movement in said chamber, means actuated by said rotor for pumping fluid, a yielding diaphragm in the pressure cavity fixed fluid-tight to and arranged to force the rotor toward one end of the pumping chamber, and means for conducting pressure accumulated by the pump to the pressure cavity, between the diaphragm and the back of the rotor.

9. A rotary pump comprising a casing containing a pumping chamber and a pressure cavity communicating with the pumping chamber, a rotor rotatable in and having an axial movement in said chamber, means actuated by said rotor for pumping fluid, a driving shaft, a sleeve keyed to the shaft so as to rotate therewith but have a longitudinal movement thereon, a diaphragm in the pressure cavity fixed fluid-tight to said sleeve and closing one end of the cavity, and means for conducting pressure accumulated by the pump to the pressure cavity between the diaphragm and the back of the rotor.

9. A rotary pump comprising a casing containing a pumping chamber and a pres-

sure cavity communicating with the pumping chamber, a rotor rotatable in and having an axial movement in said chamber, means actuated by said rotor for pumping fluid, a driving shaft, a sleeve keyed to the shaft so as to rotate therewith but have a longitudinal movement thereon, a diaphragm in the pressure cavity fixed fluid-tight to said sleeve and closing one end of the cavity, and means for conducting pressure accumulated by the pump to the pressure cavity between the diaphragm and the back of the rotor.

GEORGE W. WARDWELL.
